UNITED STATES PATENT OFFICE.

AUGUST F. ZIMMERLING, OF MILWAUKEE, WISCONSIN.

COMBINED SMOOTHING, FLUTING, AND POLISHING IRON.

SPECIFICATION forming part of Letters Patent No. 269,368, dated December 19, 1882.

Application filed April 8, 1882. (No model.)

To all whom it may concern:

Be it known that I, AUGUST F. ZIMMERLING, of Milwaukee, in the county of Milwaukee, and in the State of Wisconsin, have invented certain new and useful Improvements 5 in a Combined Smoothing, Fluting, and Polishing Iron; and I do hereby declare that the following is a full, clear, and exact description thereof.

10 My invention relates to laundry-irons; and it consists in a combined article for smoothing, fluting, and polishing, together with a device for heating the same, all as more fully set forth hereinafter.

15 In the drawings, Figure 1 is a perspective view of my entire device. Fig. 2 is an elevation of the lower part of the heating device, and Fig. 3 is a vertical longitudinal section of the same.

20 My present invention is, in part, an improvement on that patented to me on the 9th day of August, 1881, and numbered 245,336, and, like that device, has a four-faced hollow iron, A, two of the faces, *a a*, being perfectly flat 25 and designed for ordinary smoothing, while the face *a'* is intended for fluting, and the face *a''* for polishing linen. In this present case, however, instead of corrugating the entire face *a'*, as in the patent referred to, I have simply

30 made a corrugated roller, *a³*, which is journaled in lugs *a⁴ a⁴*, and extends transversely across the face *a'*, while the polishing-surface *a''*, instead of being made, as formerly, with a rounded heel simply, is here shown with its entire 35 surface curved, so that it may be used as a polisher at any point, instead of only at its rear edge, as in the patent named. These points of difference are of minor importance; but I have found by actual experiment that they

40 possess advantages over the construction shown in my said patent. The handle and locking device are formed substantially as in my said patent, and therefore do not call for an extended description here. The heating device, however, is very different in its construction and mode of operation from that shown in my said patent, and I not only attach it in a somewhat different manner, as hereinafter described, but I have also changed the position of the air-

holes A', as shown, so as to insure freer combustion within the iron, by perforating the iron near its point as well as at the rear, instead of at the rear only, as in my said patent. 50

B is the reservoir, which is filled from the end instead of the upper surface, the opening 55 being covered and protected by the screw-cap B'.

C C' C² constitute the system of feed-tubes, the first being designated the "branch," the second the "straight" tube, and the third the 60 "bent" tube. D is the regulating-tube, and E the gas-escape tube. F F' is the blow-pipe. There are four valves in my present device—namely, the feed-valve *c* in the tube C', the regulating-valve *d* in the tube D, the gas-valve *e* at the 65 end of the tube E, and the setting-valve *f* in the blow-pipe. Wherever any of the said tubes unite, or where they receive branches, I prefer to employ screw-threaded couplings, as shown, though it is obvious that my system of tubes 70 could be cast solidly, if desired, without departing from my invention, although at a greater expense, and with no increased efficiency, but rather less, as I am now enabled to take my device apart should any one of the 75 numerous tubes or valves get out of order.

The reservoir being filled with the preferred fluid—such as alcohol, naphtha, or other gaseous liquid—the feed-valve *c* is screwed upward, which opens the passage from C' to C², 80 and the fluid descends through the branch C to the straight tube C', and thence through the bent tube C² into the base of the regulating-tube D, and thence into the blow-pipe F F', and a light being applied to the burner 85 or outer end of the part F' the fluid takes fire. In a very few seconds the bent part of the tube C² becomes heated from the flame, and then all the fluid that reaches this point becomes converted into dry gas, in which form it passes 90 into the blow-pipe, just as first the fluid did, to support the flame. The heating device is then adjusted within the iron, and in an exceedingly short time the iron is heated sufficiently for the service required. As the tendency of the 95 flame is principally forward and upward, the point and uppermost surface of the iron is always kept hot, requiring only an occasional

reversing of the smoothing-surface, in ordinary ironing, whenever the operating-surface shall have become too cool, and this reversal is to be accomplished by means of the spring-catch E', here shown, and described at length in my patent already named, whereby, also, the iron may at any time be instantly set so that any face desired may be in proper position for use, and meanwhile the face above and the point 10 and sides of the iron will be getting heated in turn.

The blow-pipe consists, as indicated, of two parts, F and F'. The former communicates directly with the regulating-tube D, through 15 which it receives its supply of gas, (produced, as stated, from the fluid in the bent tube C² by the heat of the flame,) and it is screw-threaded on its outer exterior end to receive the part F', which has two air-holes, f', near the end far- 20thest from the burner. If very great heat is desired the part F' may be screwed forward, so as to more fully open these air-holes f' and increase the draft, and hence the combustion, whereas if less heat is required the part 25 F' may be screwed backward, thereby partially closing the air-passages f'. The setting-valve f controls the quantity of gas which passes to the burner; but this valve requires but little change in position, as this result can 30 be obtained under all ordinary circumstances by screwing the regulating-valve d up or down, as required. It will be understood that the four valves e, d, e, and f are identical in construction, (except that they differ in length,) 35 each valve being screw-threaded just below its head, and turning in interior screw-threaded bearings (properly packed, if required) at the upper or closed end of the tube, while each valve is pointed or tapered off at its other end 40 to fit into a correspondingly-tapered socket, so that by turning the head of the valve slightly the said valve may be screwed up or down, as required, and the space between the tapering point of the valve and its tapering seat may 45 be increased or diminished (even to the entire closing of the passage) at will, all as clearly indicated by the sectional view, Fig. 3.

The function of the gas-escape tube E and gas-valve e remains to be described. The fluid 50 in the bent tube C² becoming heated by the flame at the end of the blow-pipe expands into gas, as already described, and as this gas is formed faster than it can be consumed the balance naturally seeks an exit. The regulating-tube D being closed at its upper end, the only 55 way of escape is back through the bent tube C², and thence directly up the straight tube C'. Now, as fluid is all the time flowing from the reservoir B through the branch C into the 60 straight tube C', the said branch C is always full, and the gas cannot therefore pass into said branch, and so it continues past the coupling-point e' straight up to the top of the tube C' and out into tube E, and thence into the 65 upper part of the reservoir B, above the fluid, the tube E being on a horizontal line below

the screw-seat of the valves e and e, and therefore affording a free passage for the gas from the tube C' to the reservoir, which, however, can at any time be closed, if desired, by screwing down the gas-valve e into its socket. The effect of this heated gas on top of the fluid in the reservoir B is not only to exert a slight pressure, which insures a constant flow of said fluid out through the branch C and the other 70 feed-tubes, but, also, it prevents a vacuum being formed in the reservoir, and compels the fluid and gas to balance each other, as it were, the system of tubes being thus always 75 filled with fluid and gas while the iron is in 80 operation.

The heater is secured in place on the iron by means of its slotted plate G, which receives the flanged bolt g and its nut g', and also the pin g², the said bolt and pin projecting from 85 the rear shank of the handle of the iron, and when in place the nut g' can be screwed tight, while the pin g² prevents any swing to the lower part of the heater, thus forming a much more secure and effective lock than the plate 90 with simple key-hole slots, which I showed in my patented device hereinbefore named.

Although I have referred to my invention as an improvement in laundry-irons, I wish it understood that it is equally well adapted for 95 tailoring and dress-making, or any other business requiring the smoothing, polishing, or fluting of fabrics.

Having thus described my invention, what I claim as new, and desire to secure by Letters 100 Patent, is—

1. In a heater for combined laundry-irons, the combination of the reservoir B and system of feed-tubes C C' C², the feed-valve e, and the blow-pipe F F' and regulating-valves, 105 substantially as described, and for the purpose set forth.

2. In a heater for combined laundry-irons, the combination of the fluid-reservoir B and its branch C with the blow-pipe F F', bent 110 tube C², straight tube C', and gas-escape tube E, whereby the unconsumed gas that is formed in the bent tube C² may have passage-way into the reservoir and prevent a vacuum being formed therein above the fluid, as set forth. 115

3. In a heater for combined laundry-irons, the combination of the reservoir B, branch C, straight tube C', feed-valve e, bent tube C², regulating-tube D, regulating-valve d, and blow-pipe F F', as shown and described, and 120 for the purpose set forth.

4. In a heater for combined laundry-irons, the combination of the reservoir B, feed-tubes C C' C², regulating-tube D, gas-escape tube E, blow-pipe F F', and valves e d e f, as shown 125 and described, and for the purpose set forth.

5. In combination with the rear shank of the handle of a hollow reversible laundry-iron provided with the flanged bolt g and pin g², a heating device provided with the plate 130 G, slotted as described, whereby it may pass over the flanged bolt, and a nut g', to tighten

the plate to place, while the pin g^2 prevents any lateral movement or swing to the lower part of the heater, as set forth.

6. In a heater for combined laundry-irons, 5 the blow-pipe described, consisting of the part F, having setting-valve f, and screw-threaded on its outer end, in combination with part F', having interior screw-threads at its rear to fit over the part F, and air-holes next to its threaded portion and farthest from its burner, as and 10 for the purpose set forth.

In testimony that I claim the foregoing I have hereunto set my hand on this 21st day of March, 1882, in the presence of two witnesses.

AUGUST F. ZIMMERLING.
